UNITED STATES PATENT OFFICE.

EDMUND F. HARTSHORN, OF NEWARK, NEW JERSEY, ASSIGNOR TO STEWART HARTSHORN COMPANY, OF EAST NEWARK, NEW JERSEY, A CORPORATION OF NEW JERSEY.

SHADE-ROLLER.

1,202,284.

Specification of Letters Patent. Patented Oct. 24, 1916.

Application filed June 4, 1914. Serial No. 842,820.

To all whom it may concern:

Be it known that I, EDMUND F. HARTSHORN, a citizen of the United States, residing in the city of Newark, county of Essex, State of New Jersey, have invented a certain new and useful Shade-Roller, of which the following is a specification.

The objects of this invention are: First: to provide, in a roller without a pawl, mechanism to hold the spring in wound-up condition when it is removed from the supporting brackets. Second: to adjust the length of the roller to fit window openings of different widths. Third: to utilize the device without change as a pawl roller. These and further objects will more fully appear from the following specification and accompanying drawings, considered together or separately.

20 In the drawings: Figure 1 is a part of a window, showing a shade and roller embodying my invention; Fig. 2 is a view of the roller showing the extensible end, the parts being in section; Fig. 3 is a sectional view of the roller taken on the line 3, in the direction of the arrow, in Fig. 2; Fig. 4 is a sectional view of the roller taken on the line 4, in Fig. 2, in the direction of the arrow; Fig. 5 is a sectional view of the roller, on an 25 enlarged scale, showing the mechanism for locking the spring in wound-up condition; Fig. 6 is a sectional view, on the line 6, of Fig. 5, looking in the direction of the arrow; Fig. 7 is an end view of the cap of the roller; Fig. 8 is a view of the pawl and actuating finger; and Fig. 9 is a view of the cover plate for holding the pawl in place on the spear.

In all of the views, like parts are designated by the same reference characters.

40 My device is particularly adapted for use in car windows. Shades in such windows are provided with locking means at the bottom and they require no pawls to hold the shade in open or expanded condition. The 45 rollers have to be removed at intervals for cleaning purposes and it is desirable that when so removed the spring will be kept in wound-up condition. Therefore, one of the objects of the invention, as before stated, is 50 to hold the spring in wound-up condition when the roller is removed from its brackets. The particular mechanism for attaining this feature of the invention will be first described.

Referring to the drawings, 1 represents the roller, carrying the shade 2 wound thereon. The pin end of the roller engages with a bracket 3. The spear end of the roller engages with the usual notched bracket 4. Both of these brackets are located in the usual manner within the window frame 5. Within the roller is the usual rod 6, about which is wound the usual spring 7. At the end of the rod is a spear 8. Associated with this spear is a detent ring 9, having an opening making a very loose fit with the spear. Projecting from the inside of the ring is a pawl 10. This detent is best shown in Fig. 8 and I prefer to make it with an inclined bearing face as shown. This detent is adapted to engage with a notch 11 formed in the spear. Associated with the ring is a finger piece 12. On the outside of the spear and turning with it is a plate 13. This holds the ring in position and keeps it from dropping off the spear. In the plate 13 is an opening 14 in line with the notch 11. The purpose of this opening is to allow the operator to see the detent 10 when it is in place within the notch 11. On the end of the rod 6 is a cap 21, having an opening 22 forming a bearing for the spear. This cap is preferably flanged as shown and secured in place within the end of the roller. One part of the flange is cut away and forms a notch 23. The purpose of this notch is to allow the finger piece 12 to project outward beyond the side of the roller, and also to compel rotation of the detent with the roller. The operation of this feature of the invention is as follows: When it is desired to remove the roller from the window frame, the shade is raised or lowered until the finger piece 12 is in the up-and-down position shown in Fig. 6. The operator will then, by raising the finger piece 12 with his finger, engage the pawl 10 with the notch 11. Then by letting the shade unwind very gradually, the detent may be caused to engage with the notch so that the straight side of the detent 100 engages with one side of the notch, thereby locking the spear against rotation and preventing the unwinding of the spring. The roller may then have the end of the spear lifted out of the notched bracket 4. In placing the roller and shade back in the window frame, the pin end of the roller is introduced into the bracket 3 and then the spear is 105

introduced within the notch in the bracket 4. The shade is now unwound to a small extent which will release the notch 11 from engagement with the detent 10 and the weight of 5 the ring and finger piece will cause it to become disengaged from the notch. In car windows there is usually a hooding in order to conceal the roller and the devices for locking the detent are hidden from view. By 10 my invention, however, the operator may, by the sense of feeling, engage the detent with the notch and lock the spring in wound-up condition. In the drawings, the usual hooding is indicated by the character 24.

15 The second feature of my invention relates to means for adjusting the length of the rollers so that they may be used with window openings of different widths. Railway cars, particularly steel cars, are so made 20 that there is a slight difference in widths between various window openings. This to some extent is caused by the sagging of the frame in building the car. At intervals of time the movable fittings of the cars are 25 taken out for cleaning, and, after being cleaned, the shades are put back. The persons who do this have great difficulty in assorting the shades so that they will fit the proper windows. Any mark which may 30 have been associated with a window to identify the particular shade cannot be relied upon as it will be likely to be obliterated or removed by the varnishers and painters. I attain the second object of my invention, by 35 making the roller adjustable as to length so that it will fit any window, and will not have to be replaced in a particular window frame, by the following mechanism: I make the roller out of sheet metal, as shown, preferably tin. On the pin end of the roller is 40 an extension 15. This extension is provided with a deep channel 16. On the end of the roller is a depressed lip 17. This lip has an opening in it through which passes a screw 45 18. By depressing the lip the head of the screw will not project beyond the periphery of the roller and therefore will not disarrange the shade when wound up. Associated with this screw is a block 19. This 50 block is provided with an opening as shown. Through this opening extends a strip 20. The strip may be made of metal, such as tin. One end is hooked at 25 around the base of the channel and is secured in position thereby. The other end of the strip is 55 free and unattached as shown or it may be hooked to the base of the channel in the same manner as is the end 25. By setting the screw so that it engages tightly with the strip, the block is locked in place, and the 60 extension is held immovably upon the roller. By loosening the screw, the strip may be slid through the block due to the pulling out or pushing in of the extension to make 65 the roller longer or shorter.

The third object of the invention is to utilize the device as a pawl roller without change. It is apparent that when the spear is put in place in the bracket with the notch 11 downward, the detent 10 will never engage with the notch except when lifted up to engagement by the operator of the finger piece. If the spear be put in the bracket with the notch 11 upward and the ring be reversed, or if the detent be placed diametrically opposite to the position shown in Fig. 8, then the detent 10 will engage the notch by gravity. The device may, therefore, be used as an ordinary pawl spring roller, thus making the fitting of general application. The device, therefore, although particularly adapted for use with spring rollers without pawls, may be, by a simple reversal when introduced within the bracket, made to act and function as a pawl shade 80 roller.

In accordance with the provisions of the patent statutes, I have described the principle of my invention, together with the apparatus which I now consider to represent 90 the best embodiment thereof; but I desire to have it understood that the apparatus shown is merely illustrative and that the invention can be carried out in other ways.

Having now described my invention, what 95 I claim as new and desire to secure by Letters Patent, is—

1. A shade roller, a spring carried by the roller, a spear carried by the roller, connections whereby the spring may rotate the 100 roller relatively to the spear, a notch in the spear, of a ring loosely carried on the spear, a detent on the ring, said detent being normally out of engagement with the notch, means for manually rotating the roller 105 against tension of the spring; and manually operated means for engaging the detent with the notch to prevent unwinding of the spring.

2. A shade roller with a spring and a 110 spear, said spear having a notch, in combination with a detent adapted to engage with the notch, a finger piece associated with the notch, and a plate, there being an opening in the plate adjacent to the notch through 115 which the engagement of the detent with the notch may be observed.

3. A tubular roller and a slotted block carried by the roller, in combination with a tubular extension telescoping within the 120 roller, a tongue secured to the extension and extending through the block, and a screw for securing the tongue to the block.

4. A shade roller, formed of sheet metal, with a depressed lip at one end, and an extension with a longitudinal channel therein, said channel containing a tongue secured thereto, in combination with a block having an opening therein through which the tongue slides, and a screw passing through 130

the block and engaging with the strip, said screw engaging and being supported by the depressed lip on the roller.

5. A tubular roller and a slotted block carried thereby, in combination with a tubular extension telescoping within the roller, a channel extending lengthwise the extension, a tongue lying within the channel and secured at one end thereof passing through

the slot in the block and a screw carried by 10 the roller for engaging the tongue with the block.

This specification signed and witnessed this second day of June, 1914.

EDMUND F. HARTSHORN.
